MAGAZINE PENCIL

Hans Maucher, New York, N. Y.

Application January 18, 1938, Serial No. 185,488

10 Claims. (Cl. 120—14)

The present invention relates to magazine pencils, and more particularly to multi-lead magazine pencils in which a plurality of lead carrying and lead propelling members are arranged to be selectively disposed, one at a time, for writing purposes.

In pencils of the type to which the present invention relates it is important to lock the various parts together in firm and secure assembly, so as to prevent the user from readily dismantling the pencil in the normal and natural urge to take things apart, usually resulting in inability to reassemble and in damaging the parts so as to make the pencil inoperative and out of order even if reassembled. At the same time it is necessary to make such pencils readily dismantlable without any damage, for repair purposes. In the multi-lead pencils heretofore used, the simultaneous attainment of both objects has been difficult and costly. In such pencils, as previously made, the locking of the parts has been accomplished either by soldering them together or by means of complicated and costly arrangement of parts which included bayonet joints and locking collars, which were costly to make, difficult to put together and practically impossible to take apart for repair and reassembled without some damage.

The present invention contemplates the improvement of magazine pencils of the character described by providing a new and novel construction whereby the various parts making up the pencil may be economically made and may be easily and economically assembled into a rigid and secure unit, and which may, nevertheless, be readily taken apart and reassembled, for purposes of repair, by anyone conversant therewith, without any danger of damaging or spoiling any of its parts.

Multi-lead magazine pencils heretofore found in the art have been of comparatively large circumference and bulk due to the necessary provision of the plurality of lead carrying and propelling elements and their associated mechanisms and means for their selective disposition in operative writing position. This relatively greater bulk has been a deterrent factor to the greater and more extensive use of such pencils.

The present invention, therefore, further contemplates the provision of multi-lead pencils with a new and improved type of lead carrying members whereby such pencils may be made of a lesser bulk than heretofore possible, thereby overcoming this objection to their more general and more prevalent use.

One practical embodiment of a compact, firmly and securely assembled and readily repairable multi-lead magazine pencil of the present invention, possessing many additional advantages which will be readily apparent to those skilled in the art, is illustrated in the accompanying drawing in which

Fig. 1 is a side elevational view of the upper portion of a barrel of a pencil of the present invention, partly broken away to show details 10 of the novel assembling means provided thereon;

Fig. 2 is a similar, partly broken away, view of a combined barrel closure and spare lead magazine, showing details of the assembling means provided thereon;

Fig. 3 is a similar view, partly broken away, of a clip bearing outer sleeve cap showing details 15 of the assembling means provided thereon;

Fig. 4 is a cross sectional view of the magazine taken along line 4—4 of Fig. 2;

Fig. 5 is a cross sectional view of the barrel taken along line 5—5 of Fig. 1;

Fig. 6 is a side elevational view of the assembled pencil of the present invention, partly in vertical section to show details of the lead carrier arrangement and the lead carrier disposing mechanism;

Fig. 7 is an enlarged fragmentary vertical sectional view of the bead lock for the barrel and magazine of the pencil assembly; and

Fig. 8 is a cross sectional view taken through the barrel and lead carrier elements of a pencil of the present invention, looking down into the barrel.

The drawing shows, in detail, a pencil 10, 35 comprising a barrel 12, preferably tubular, and of any desirable suitable material, thickness and length. The barrel may be provided, preferably integrally, with the usual conical writing tip 14, having a lead passage 16.

On the sides of the barrel, preferably at a point substantially above the tip 14 are provided a number of oblong openings 18, preferably regularly spaced and equal in number to the leads intended to be provided, shown in the 45 illustrated embodiment as four. A longitudinal slot 20 extends upwardly from one side of each of said oblong openings 18, thereby forming a shoulder 22. Each such slot is widened at a point below the top of the barrel into a second 50 oblong space 24, from the upper end of which, and preferably to one side thereof, a slit 26 continues to the top of the barrel forming a shoulder 25, and thereby splitting the upper portion of the barrel into several vertical segments, 55

which may be readily and resiliently spread apart to a limited extent, enabling the continuous slots to serve a double purpose, as will hereinafter be made clear.

5 In the barrel 12 are positioned the desired number of lead carriers, generally designated at 28. Each carrier comprises an arm 30 at the lower end of which is provided a lead holding tube 32 containing a lead 34, the tube 32 being 10 provided adjacent its free end with lead advancing means 36 of any of the well known types which it is not thought necessary to show in detail.

While heretofore the arm 30 was made of 15 either cylindrical or rectangular tubing uniform throughout its length, I provide, for purposes of compactness an arm 30 which has its upper portion 38 of triangular shape so that a plurality of the arms may be nested together with their 20 apices converging, in a relatively small space, thereby enabling the use of a barrel of smaller cross section than heretofore possible.

Each of the carriers 28 is supported at its upper end on the shorter leg 40 of an inverted 25 V-shaped preferably flat spring 42, which arm is secured on an inner wall of the triangular portion 38 of the carrier arm 30. The longer leg 44 of the spring extends downwardly alongside of the triangular carrier arm portion 38, terminating in an inwardly turned lug 46. Carried on the spring leg 44, preferably by means of a thin vertically elongated neck 50, which is sufficiently thin to be readily reciprocated in the slot 20, is a knob 48, which is disposed exteriorly of 35 the barrel 12, whereby the respective lead carrier may be manipulated from the exterior of the barrel.

To keep the carriers 28 in normally inactive position, that is, out of the opening 16, there is 40 provided within the barrel 12 a coiled expansion spring 52, one end of which is supported on the converging walls of the conical tip 14, or on any suitable means that may be provided within the barrel to anchor the same, and the other end of 45 which may be enclosed within the sleeve 54, fitting snugly within the barrel, and having an in-turned flange 56 which impinges on the upper edge of the spring and which also serves to support the lugs 46 to keep the lead carriers in a 50 normally upwardly disposed position.

It will be apparent that the lead carriers may be readily arranged in their place by inserting their lower portion into the barrel and passing the neck 50 through one of the slots and letting 55 the carrier go down until the lug 46 rests on the flange 56 of the collar 54, the lower portion of the carrier including the lead holder and lead advancing means being disposed within the coiled spring 52. It will also be apparent that the 60 springs 44, which present a flat side of their respective carriers to the barrel wall, will tend to nest the upper ends of the carriers with their apices converging to occupy a relatively small space, and that at the lower ends of the carriers 65 where the springs do not reach to occupy part of the barrel, there will be sufficient space for the round portion of the carrier arms.

It may here be stated that the relative proportions and arrangement of the barrel, the lead carriers and the slot 20 and its various enlargements may be so regulated and so disposed that 70 normally the spring 52 and collar 54 supporting the lug 46 will dispose the end of the lead carrier and the lead at a point above the tip 14, 75 and the neck 50 will be disposed in the slot

enlargement 24 pressed upwardly against the shoulder 25. The proportions and disposition of such carriers and slots may also be such that when the head is pressed downwardly until the neck is caught by the shoulder 22 of the slot 5 enlargement 18, the end of the lead holding member 32 with at least part of the lead advancing mechanism 36 sufficient to be gripped by the fingers for manipulation, will project in operating position from the tip opening 16. The 10 spring 52, which is thereby compressed, will tend to press the neck 50 firmly upwardly against the shoulder 22, which pressure, together with the support provided by the edges of the opening 16 15 will keep the carrier and the lead in relatively firm operating position.

The non-operating carriers will remain in their normal upwardly disposed position, even though the support of the spring 52 is withdrawn, by the pressure of the spring leg 44, against the 20 barrel wall and by engagement of the lower edge of the neck 50 by the lower edges of the respective slot enlargements 24.

To release any carrier from writing position, all that is necessary is to turn the knob 48 to 25 disengage the neck 50 from the shoulder 22 and direct it into the slot 20. The spring 52 will expand to push the carrier and lead out of operating position to normal.

To close the barrel against removal of the carriers therefrom, I provide a combined closure and spare lead magazine 58 having the bottom 60 and a thread 62 at its upper end. The magazine is adapted to be fitted into the upper end of the barrel in which it is held against removal 30 by an inwardly pressed annular bead 64 formed near the upper edge of the barrel, at a point substantially above the enlarged recess 24, which meshes into a cooperating groove 66 provided on the magazine at a point sufficiently close to the 40 bottom thereof so that it may clear the recess enlargement 24 when it is in operative position. The magazine is locked against removal from the barrel by means of an open ended sleeve 68 which fits snugly over the upper end of the barrel, 45 holding its segments together and forcing the bead 64 against the groove 66. The upper end of the sleeve may be swaged, as at 70, to form a thread engaging edge by means of which the sleeve may be firmly threaded in locking engage- 50 ment on the magazine.

It will be readily apparent that there is a co-operating locking arrangement between the sleeve and the magazine. The sleeve locks the magazine in the barrel by keeping the barrel head 55 within the magazine groove, and the magazine locks, by its thread, the sleeve upon the barrel, against removal.

The sleeve may be provided with the usual pocket clip 72, and an eraser 74 may be engaged 60 within the thread 62 to close the magazine to keep spare leads therein.

This completes the description of the multi-lead magazine pencil of the present invention. It will be seen that such pencil is of greater compactness than heretofore possible because of the triangular upper ends of the lead carrier arm and that such pencil may be more economically produced both because of the simplicity and low cost of the assembly mechanism and of the assembly operation. The latter economies are entirely made possible by splitting the barrel into several parts along an extension of the lead carrier guiding slots 20. First, it makes possible the rapid and ready insertion of the carriers in 70 75 80 85 90 95 98 99 100

position, eliminating the slow and tedious process heretofore used which required manipulation of the carriers and their springs within the barrel to project their knobs outwardly through a small opening, an operation which was particularly difficult after the first carriers were in place occupying a large part of the barrel volume.

The segmentation of the barrel also makes possible the assembly of the barrel closure arrangement because the barrel thus becomes sufficiently resilient to permit the insertion of the magazine past the bead 64, which reduces the barrel cross section.

It is to be noted that this segmentation in no way weakens the barrel and that in general the effectiveness of the pencil of the present invention in practical use is, if anything, increased, by virtue of its compactness and lesser bulk.

This completes the description of a preferred embodiment of the multi-lead pencils of the present invention. As, obviously, many variations may be made in the embodiment disclosed, within the spirit and scope of the present invention, I do desire to be protected for any such variations in accordance with the broadest interpretation of my invention and of the claims here-to appended.

I claim:

1. In a magazine pencil having a barrel and lead carrying mechanism disposed within the barrel, a barrel closure comprising a lead magazine disposed within an open end of the barrel and means for locking the magazine within the barrel comprising an inwardly pressed annular bead formed on the barrel, said barrel having a plurality of longitudinal slits extending from the open end thereof past the said bead and resiliently segmenting said open end, a groove upon the magazine adapted to engage and nest upon the said bead, a sleeve cap fitting over the barrel and magazine and cooperating means upon the sleeve and magazine for engagement of the one by the other to lock the sleeve cap upon the barrel.

2. In a magazine pencil having a barrel and lead carrying mechanism in the barrel and an open end where-through the mechanism is inserted into the barrel, closure means for the open end comprising a laterally resilient open end on the barrel having an inwardly formed annular bead thereon, a closure member having an annular groove adapted to engage and nest the said bead fitted into the said open end of the barrel and partly projecting therefrom, and a sleeve cap engaging the projecting end of the closure and fitting over the open end of the barrel to press the same against the closure.

3. In a magazine pencil having a barrel and lead carrying mechanism in the barrel and an open end where-through the mechanism is inserted into the barrel, closure means for the open end comprising a laterally resilient open end on the barrel having an inwardly formed annular bead thereon, a closure comprising a spare lead magazine having an annular groove adapted to engage and nest the said bead fitted into the said open end of the barrel and partly projecting therefrom, and a sleeve cap engaging the projecting end of the closure and fitting over the open end of the barrel to press the same against the closure.

4. In a magazine pencil having a barrel and lead carrying mechanism disposed within the barrel, barrel closing means comprising a lead magazine partly disposed with an open end of

the barrel and means for locking said magazine within the barrel comprising an inwardly pressed annular bead formed on the barrel adjacent said open end, a plurality of longitudinal slits extending from the edge of the said open end past the said bead, whereby the said end is made laterally resilient, a cooperating groove on the magazine engaging the said bead, a thread upon the projecting end of the magazine and an open ended sleeve cap having one end fitting over the barrel to press the same against the magazine and the other end swaged and screwed upon the magazine thread.

5. In a magazine pencil having a barrel lead carrying mechanism within the barrel and an open end wherethrough the lead carrying mechanism is inserted into the barrel, closure means for the barrel comprising a longitudinally slotted upper end, whereby the said end is resiliently segmented, an inwardly formed projection on the segment end of the barrel, a closure member having a depression adapted to receive the said projection partly fitted into the said segmented barrel end, a sleeve cap fitting over the segmented end of the barrel to press the same against the closure, and engaged upon the projecting end of the closure against removal from the barrel.

6. In a magazine pencil having a barrel, lead carrying means within the barrel and an open end wherethrough the lead carrying means are inserted into the barrel, closure means for the barrel comprising a closure member partly fitted into the open end of the barrel, cooperating engaging means upon the barrel and closure adapted to prevent the withdrawal of the closure from the barrel and means engaged upon the projecting end of the closure and fitting over the open end of the barrel to lock the said cooperating engaging means on one another.

7. In a multi-lead magazine pencil having lead carriers and means for manipulating said lead carriers in and out of operative position, a housing for the carriers comprising a barrel having a conical writing end and longitudinal slots extending from a point above the writing end to the other end of the barrel, whereby the barrel is resiliently segmented and wherethrough the lead carrier manipulating means may be reciprocated and projected to the exterior of the barrel for manual engagement, a shoulder formed at the lower end of each slot adapted to engage the lead carrier manipulating means to dispose and retain the lead carrier in operative position, an inward projection formed on the barrel adjacent its upper end, a magazine closure having a cooperating depression adapted to receive the said projection partly fitted into the said open end of the barrel, a thread formed on the projecting end of the magazine and an open ended sleeve cap fitting over the open end of the barrel to press its segmented parts against the magazine, the upper end of the sleeve cap being swaged and screwed upon the projecting end of the magazine.

8. A multi-lead magazine pencil comprising a barrel having a tapered writing end and a plurality of slots extending longitudinally from a point above the tapered end to the other end of the barrel whereby the barrel is resiliently segmented, a plurality of lead carriers disposed within the barrel, each lead carrier having an upper portion of triangular cross section and carrying a depending spring adapted to impinge against the barrel wall to press an apex of the

carrier toward the center of the barrel, carrier manipulating means fixed on each spring projecting through a slot to the exterior of the barrel whereby the carrier may be reciprocated within the slot in and out of operative position, spring means within the barrel to normally oppose movement of the carriers into operative position, a shoulder formed on the lower end of each slot adapted to engage the lead carrier manipulating means to dispose it in operative position against the pressure of the said spring means and closure means for the barrel to prevent removal of the lead carriers therefrom comprising a closure member having an annular groove fitting into the end of the barrel and extending thereabove, an annular bead formed internally on the resiliently segmented portion of the barrel adjacent the upper end thereof and adapted to fit within and engage the said groove, and a sleeve cap fitted over the segmented end of the barrel to press the said bead into the said groove and engaged upon the projecting end of the spare lead magazine against removal from the barrel.

9. A multi-lead magazine pencil comprising a barrel having a tapered writing end and a plurality of slots extending longitudinally from a point above the tapered end to the other end of the barrel whereby the barrel is resiliently segmented, a plurality of lead carriers disposed within the barrel, each lead carrier having an upper portion of triangular cross section and carrying a depending spring adapted to impinge against the barrel wall to press an apex of the carrier toward the center of the barrel, carrier manipulating means fixed on each spring projecting through a slot to the exterior of the barrel whereby the carrier may be reciprocated within the slot in and out of operative position, spring means within the barrel to normally oppose movement of the carriers into operative position, a shoulder formed on the lower end of each slot adapted to engage the lead carrier manipulating means to dispose it in operative position against the pressure of the said spring means and closure means for the barrel to prevent removal of the lead carriers therefrom comprising a spare lead magazine member having

an annular groove fitting into the end of the barrel and extending thereabove, an annular bead formed internally on the resiliently segmented portion of the barrel adjacent the upper end thereof and adapted to fit within and engage the said groove, and a sleeve cap fitted over the segmented end of the barrel to press the said bead into the said groove and engaged upon the projecting end of the spare lead magazine against removal from the barrel.

10. A multi-lead magazine pencil comprising a barrel having a tapered writing end and a plurality of slots extending longitudinally from a point above the tapered end to the other end of the barrel whereby the barrel is resiliently segmented, a plurality of lead carriers disposed within the barrel, each lead carrier having an upper portion of triangular cross section and carrying a depending spring adapted to impinge against the barrel wall to press an apex of the carrier toward the center of the barrel, carrier manipulating means fixed on each spring projecting through a slot to the exterior of the barrel whereby the carrier may be reciprocated within the slot in and out of operative position, spring means within the barrel to normally oppose movement of the carriers into operative position, a shoulder formed on the lower end of each slot adapted to engage the lead carrier manipulating means to dispose it in operative position against the pressure of the said spring means and closure means for the barrel to prevent removal of the lead carriers therefrom comprising a spare lead magazine having an annular groove adjacent its bottom fitting into the end of the barrel, extending thereabove and terminating in a threaded end, an annular head formed on the resiliently segmented portion of the barrel adjacent the upper end thereof and adapted to fit within and engage the said groove and a sleeve cap fitting over the segmented end of the barrel to force and retain the said bead in the said groove, said sleeve cap being swaged at one end whereby it is screwed upon the said magazine to prevent removal from the barrel.

HANS MAUCHER.
